UNITED STATES PATENT OFFICE

2,503,663

PRESERVATION OF FRESH CITRUS FRUITS

Carl E. Gericke, Clewiston, Fla., assignor to American Machinery Corporation, Orlando, Fla., a corporation of Florida

No Drawing. Original application August 23, 1946, Serial No. 692,701. Divided and this application April 25, 1949, Serial No. 89,559

3 Claims. (Cl. 99—154)

1

This is a division of my co-pending application Serial No. 692,701, filed August 23, 1946.

This invention relates to the commercial preparation of fresh whole fruit for the market wherein in fungus control agents are applied thereto.

The essential object of the present invention is the treatment of whole citrus fruit with an acid bath.

It is well known to use fungicides in an alkaline bath in order to reduce the spoilage of fruit after or during the treatment or preparation of the fruit for the market and one of the well known fungicides is sodium benzoate. However in the composition of the bath of the present invention, less fungicide—i. e., sodium benzoate, sodium borate, sodium hypochlorite, calcium hypochlorite and others commercially available—is required to preserve the fruit because of the acid nature of the bath, medium or carrier than in an alkaline bath of the prior art, the bath of the present invention enhancing the activity of the fungicidal agent toward the fruit. It is therefore within the contemplated scope of this invention to use approximately 1% of fungicide under the existing acid condition of the bath of the present invention where previously it has been necessary to have 1% or more of the fungicide present in the baths of the prior art.

This invention contemplates the use of an aqueous bath incorporating a fungicidal agent and a surface active agent which has outstanding characteristics as hereinafter more specifically set forth, but does not contemplate the use of a solvent as disclosed in the prior art, which solvent removes the natural waxy coating from the fruit and is absorbed by and contaminates the peel thereof.

It has been found practical to employ the bath, above referred to, in the coloration of oranges as set forth in my co-pending application, above mentioned, and in which bath an oil-soluble water-insoluble edible dye is incorporated; and it has also been found practical in this bath, containing the dye, to incorporate the fungicidal agent of the present invention. However, it is to be understood that the fungicidal agent alone may be incorporated in the bath of the present invention without the dye.

Certain surface active agents have several general uses, one of which is a dispersion of a solid into a liquid to produce a suspensoid. These surface active agents fall into three general classifications, hydrophilic, anionic and cationic. The cationic and anionic compounds are usually long chain carbon compounds with a terminal grouping capable of ionizing when put into solution in an aqueous solvent. When finely divided material, which is to be emulsified or dispersed, is placed or produced in such a solvent containing an ionized surface active agent, the mole-

2

cules of the ionized surface active agent orient themselves so that the carbon chain of the molecules either dissolve in or are attracted by the finely divided material to be emulsified or dispersed, while the terminal groupings bearing the charge of the molecules extend into the solvent. In this manner an aggregation of finely divided and stabilized particles are formed in the solvent, each of which are stabilized by one or more electric charges. The surface active agents used in carrying out the present invention are of the cationic type which offer many advantages over the other two types of surface active agents previously used.

The anionic surface agents with respect to structure are typified with respect to molecular configuration by a long carbon chain molecule such as a fatty acid which bears a negative charge when acting as an emulsifier or dispersing agent. On the other hand the cationic agents can be typified by a long carbon chain molecule with a terminal nitrogen containing group which bears a positive charge when acting as a stabilizer for an emulsion or suspensoid.

In carrying out the present invention an organic amine salt solution is mixed, with or without heating (heating being used to accelerate solution) with a fungicidal agent to form a concentrate. This concentrate is further diluted with water to make a bath for the treatment of citrus fruit. The organic amine salts that fall within the scope of this invention are the amine salts of a monobasic acid either organic or inorganic. The amines from which these salts are made must have one or more of the hydrogen atoms attached to the nitrogen replaced by hydrocarbon radicals. It has been found that not all of the compounds falling within this class will work satisfactorily, but only those compounds wherein at least one of the hydrocarbon group contains 10 to 18 carbon atoms. It should further be related that the secondary and tertiary compounds should contain only one carbon chain of the type just specified and that the second side grouping in the secondary amine and the second and third side groups in the tertiary amine should contain as few carbon atoms as possible. The description herein given should not be construed to mean that ring configurations must be absent since it has been found that some compounds consisting of a long carbon chain molecule to which is molecularly attached a nitrogen containing ring are also effective in the salt form as a surface active agent.

The acids used are monobasic acids such as hydrochloric, hydrobromic, acetic, formic, lactic, etc. It is well known that many commercial amines on the market are handled under trade names and are sometimes a mixture of amines

rather than a pure compound. These mixtures are satisfactory. The Sharples Chemical Company and Armour & Company are two corporations marketing such amines.

The following compounds have been tried:

Trade name or designation by Armour & Company as of 1945

Amines, present-primary	Chain Length	AM-1120	AM-1140	AM-1160	AM-118.5-B	AM-1180	AM-Coco-B
		Per cent	Per cent	Per cent	Per cent	Per cent	Per cent
Octyl	C ₈						8
Decyl	C ₁₀						9
Dodecyl	C ₁₂	90	4				47
Tetradecyl	C ₁₄	9	90				18
Hexadecyl	C ₁₆		4	90	30	6	8
Octadecyl	C ₁₈			6	25	93	5
Octadecenyl	C ₁₈	1	2	4	45	1	5
Ave. Mol. Wt.		185	213	244	263	267	200
Primary amine by titration		97	97	97	97	97	97
Approx. melting point, °C.		24	29	38	41	55	21

All were of the "purified" grade (distilled).

Any one of the above amines or any mixture thereof may be employed. In addition to those compounds in the above table, the compounds known as AM-2120 and AMCL-4 Coco-C may be employed, the first compound consisting primarily of didodecyl ammonium chloride (secondary amine) and the second compound consisting of a mixture of quaternary ammonium salts containing an aliphatic side chain having 12 to 14 carbon atoms. The best results were obtained with AMCL-4 Coco-C and AM-Coco-B and AM-2120.

As one example or formula for practicing the invention, mix the desired amount of the fungicidal agent (as above mentioned) and 18 pounds of AM-Coco-B and heat, preferably with stirring, the necessary amount of hydrochloric or acetic acid being added to neutralize the amine; and, preferably, when the amine or AM-Coco-B has melted (if previously in a solid state) sufficiently to be incorporated with the other ingredients of the mixture, water is added to about 20 gallons to form a concentrate. This concentrate is further diluted to make a bath by adding it to 25 parts of water for each part of concentrate. The fruit is contacted by floating and submerging them in said bath. The temperature of the bath may be as much as between 104° F. to 118° F. for a period of 4½ minutes. It is to be noted that the temperature employed is well below the legal maximum of 127° F. allowed by law for treatment of citrus fruit. The temperature of the bath may be reduced from that stated, provided the oranges remain therein for a longer period of time. The bath is acid in reaction as it contains the salt made by the combination of a weak base and a strong acid.

The other amine compounds, mentioned above, may be mixed and prepared with the fungicidal agent and water in substantially the same manner and proportions as stated in the example or formula just given. This formula may be further enhanced by the addition of a small amount of alpha terpineol as an anti-foaming agent, but this is not necessary.

It is well recognized that the smallest possible amount of fungicidal substances is highly desirable as they are not beneficial to the human system. Certain laws have been passed limiting the use to less than a given percentage of preservative materials. It is, therefore, easily seen that a lower percentage of sodium benzoate or other fungicidal material would be highly de-

sirable if equivalent fungicidal protection could be obtained which is the case with the present invention. Practically all of the materials now used for fungicidal purposes are more active in 5 an acid medium and therefore much less of the

fungicidal agent is necessary to produce the desired result.

Among the advantages of this bath and process 25 over existing baths and processes is the fact that water containing iron or other dissolved mineral matter, such as hard water as is found in those communities where limestone or coral formations are common, may be used directly without a preliminary treatment. This is possible because the 30 bath is acid in reaction and not alkaline as is used today. Therefore, the alkaline earth and metallic elements remain in solution rather than precipitate out as soaps. These would foul the 35 bath and render it inoperative.

Having thus fully described my invention and 40 set forth as well as possible the composition of the compound purchased under trade names so as to enable others skilled in the art to use and compound the same, I claim as my invention and desire to secure by Letters Patent the following:

1. A bath for the treatment of citrus fruit containing a fungicidal agent and a substituted ammonium salt having at least one hydrocarbon 45 chain of 10 to 18 carbon atoms.

2. In a process for the prevention of mold 50 growth in citrus fruit, the step of bringing the fruit into contact with a fungicidal agent in an acid bath containing the salt of amine having at least one hydrocarbon side chain of 10 to 18 carbon atoms.

3. In a process for the prevention of mould 55 growth in citrus fruit, the step of bringing the fruit in contact with a bath containing a fungicidal agent and an aliphatic substituted amine salt of a strong acid, said amine having at least one hydrocarbon side chain of 10 to 18 carbon atoms, and said bath having an acid reaction by virtue of the salt contained therein.

60 CARL E. GERICKE.
